UNITED STATES PATENT OFFICE.

JACOB GARNETT JOHNSON, OF IVANHOE, VIRGINIA, ASSIGNOR OF FOUR-TENTHS TO ALBERT K. GROSECLOSE, OF IVANHOE, VIRGINIA, AND THREE-TENTHS TO MARCO R. HILLEBERG, OF CROCKETT, VIRGINIA.

RAILWAY MAIL CATCHING AND DELIVERING MEANS.

1,123,127.

Specification of Letters Patent. Patented Dec. 29, 1914.

Application filed March 30, 1914. Serial No. 828,276.

To all whom it may concern:

Be it known that I, JACOB GARNETT JOHNSON, residing at Ivanhoe, in the county of Wythe and State of Virginia, have invented 5 certain new and useful Improvements in Railway Mail Catching and Delivering Means, of which the following is a specification.

My invention, which has reference to mail 10 bag transferring mechanism in which the operation of delivering the mail pouches into the car and discharging the pouches from the car, is practically simultaneously effected, has for its object to provide a mechanism of the general character stated of a 15 simple and economical construction which effectively serves its intended purposes.

With the above and other objects in view 20 my invention consists in the peculiar construction and novel arrangement of the parts hereinafter explained, specifically pointed out in the appended claim and illustrated in the accompanying drawings, in which:—

Figure 1 is a perspective view of my 25 proved mail bag transferring mechanism, the parts being shown at their operative position. Fig. 2 is a top plan view of the stationary bag holding member. Fig. 3 is a plan view of the bag holding and catching 30 devices located within the car doorway, the same being shown at their inner or turned back position in dotted lines. Fig. 4 is a detail side elevation of the vertically adjustable catcher arm standard or holder 35 mounted on the car door, the catcher arms being shown swung to their vertical or inoperative position. Fig. 5 is a detail view of the turning lever and its coöperating spring device, hereinafter referred to. Fig. 6 is a 40 detail view hereinafter specifically referred to. Fig. 7 is a detail view of the hub with the sockets 17—17.

In the practical arrangement of my present invention, the same comprises a hollow 45 standard 1, located at one side of the track, and in which is supported a post or shank 2, the latter being adjustably held in the said standard 1, by a set screw 13 to thereby provide for raising and lowering the mail bag 50 holding and catching devices mounted thereon to a proper horizontal position for co-operating with the mail bag delivering and

catching means carried by and adapted for being projected beyond the side of the car. A counterpoise 23 is attached to the inner 55 end of the arm 21, which tends to normally swing the said catching and delivering devices to an upright position. To hold the said devices to their down or operative position, I provide a cable 5 that connects with the post 2, and which has a rod 6 having an eye attached to it, the purpose of which is to hook over an upper stud pin *a* that projects laterally from the head 25.

When the parts are held down, as shown 65 in Fig. 2, the rod 6 is held to a vertical position by engaging a lower stud pin *b* and over the passageway between the upper and lower arms 22—22^a, such positioning of the rod 6 being provided for automatically tripping the said catching and delivering devices, which operation is effected in the manner presently explained. Each of the upper arms has a pair of lateral extensions 61 that 70 form the hangers upon which the mail bags 75 (to be caught by the bag catching means on the car) are suspended. Each extension 61 includes a flat spring 60 whose outer end is turned up to facilitate the placing of the bag loop therein, as shown.

7 designates a catcher finger or extension, one of which is projected laterally from each of the lower arms 22^a, and the said extensions 7 are disposed midway of the two upper extensions 61—61, it being understood that 85 the said member 7 catch the bag that is carried forward by the bag holding devices on the car, see Fig. 1.

The mail bag catching and delivering mechanism mounted upon the car in my 90 present construction, comprises a body or hub member 8 slidably held upon a standard 9, located in the car doorway and the said member is held to its vertical adjustments upon the standard by a bottom or disk member 10 that is adjustably held by set screw 4, and an upper collar 12 provided with a set screw 12^a.

14 designates a shaft that extends from the hub 8 in a plane at right angles to the 100 standard, and the said shaft is rockably mounted in the hub, so that it may be readily turned to bring the catching and delivering devices mounted on the outer end there-

of, either to the horizontal or operative position shown in Fig. 1, or to the vertical or inoperative position shown in Fig. 4.

The inner end of the shaft carries a crank handle 15 having the usual spring latch that includes a stud 16, adapted for interlocking with either of a pair of sockets 17-17, in the hub member, it being understood that when the shaft is at the position shown in Figs. 1 and 3, the stud engages with one of the said sockets and holds the parts locked to such position, and likewise when the shaft is turned to bring the parts to the position shown in Fig. 4, the said stud 16 engages 15 the other socket and holds the parts locked to the latter position.

The catching and delivering devices carried upon the car comprise a pair of fingers or extensions 18-18, each of which has a clip spring 19 that opens outwardly over the outer end of the finger 18, and is so arranged that the loop or handle 30 of the mail bag can be readily slipped in place and caught on the notched outer end of the said 25 extensions to be held in position for being passed over the stationary catcher finger 7, whose outer end is suitably notched to prevent the bag loop from jumping off the said finger when caught thereby.

30 31 designates a catcher spring mounted over the inner end of the arms 18, and it is so positioned with respect to the notched inner end of the said arms that as the said arms 18 (which arms, it should be stated, are 35 closer together than the extensions 61 that hold the bag to be caught) pass through the loop or handle of the stationarily held bag they catch the said bag loop or handle which passes under the catcher spring 31.

40 For holding the hub 8 with its attached devices locked to either the operative position shown in Figs. 1 and 2, or to the position shown in Fig. 4, a lever 32 is pivotally mounted in a vertical recess 33 in the hub 8 which when the parts are as in Figs. 1 and 3, is swung down for engaging a notch 34 in the disk which also has a second notch 35 with which the said lever is brought into engagement for locking the parts when the 45 hub 8 is turned and the shaft is rocked to bring the catching and delivering elements to the position shown in Fig. 4.

By reason of constructing and arranging the parts as shown and described, the mail 55 pouch transferring devices located on the trackway, can be readily adjusted to the desired vertical position, for a proper coöperation with the like devices carried by the car, which being also vertically adjusted can be 60 set to work in harmony with the other or stationarily held transferring devices. It should be stated, however, that in addition to providing for the vertical adjustments of the two sets of devices, the arms 22-22^a of 65 the stationary catching and delivering mech-

anism are spaced apart sufficiently to allow for the usual vertical vibration of the car held catching and delivering means caused by the undulations of the road bed and the usual spring vertical motion of the car, 70 without danger of effecting a proper coöperation of the two sets of devices or of damaging them.

When the parts that constitute my mail catching mechanism are positioned as shown 75 in Fig. 1 of the drawings, which indicate a mail bag hung in position for being transferred from the car to the catcher devices at the station and a mail bag hung in position on the arm 21 to be caught up by the 80 catching devices on the car, as the car travels in the direction of the arrow on Fig. 1, the catcher fingers 18-18 pass between the members 22-22^a on the arm 21 and through the loop or handle 30 of the mail bag hung 85 from the said arm 21. As the catcher devices on the car travel forward as stated, the shaft 14 of the said device engages the mail bag loop 30 before mentioned and the latter is pushed off the extension 61-61 90 onto the arms 18-18 and caught up by the spring catcher 31-31 mounted thereon. During the aforesaid operation the loop 30 of the mail bag to be delivered from the car passes over the catcher finger 7 on the arm 95 21 and is caught up by the said finger 7. As the shaft passes through the members 22-22^a of the arm 21 it engages the detent 6 and releases the detent 6 and thereby frees the said arm 21 which, after the rear-most 100 arms 18-18 of the moving catcher devices pass from between the members 22-22^a, then swings up to the vertical position.

From the foregoing description taken in connection with the accompanying drawing, 105 the complete construction, the operation and the advantages of my present invention will be readily understood by those skilled in the art to which the said invention relates; it being apparent that by reason of the duplex 110 arrangement of the parts the same operation of catching and delivering the mail pouches occurs when the car travels in either direction.

One of the advantages of my present invention is that since the devices alongside of the track are rockably mounted and tiltable to the vertical out of the way position by the counterpoise 24, by placing the eye bolt that holds the said devices down in the 115 path of movement of the outer end of the arm that projects from the car, see Fig. 6, as soon as the pouch transferring operation is completed the said arm engages the rod 120 moves it off the stud 7 and thereby releases 125 the tilttable devices which then automatically return to the upright position.

What I claim is:

In a mail bag transferring means of the character described: a standard mounted in 130

the car door way, a supporting body rotatably mounted on the standard, means for locking the said body in different positions on the standard, a catcher, said catcher including a shaft rotatably mounted on the said body, bag catching elements on the outer end of the said shaft, a crank handle on the inner end of the shaft

and a latch device carried by the crank handle for locking with the body to hold the shaft at different rotated positions.

JACOB GARNETT JOHNSON.
